CLOTHING

Samuel Rosenblatt, New York, N. Y.

Application April 10, 1936, Serial No. 73,676

3 Claims. (Cl. 2-93)

This invention relates to clothing. It is particularly directed to a snow suit and coat combination garment and the like articles of wearing apparel.

5 An object of this invention is to provide a garment of the character described comprising a snow suit having means to convert the jacket thereof into a coat.

A further object of this invention is to provide 10 a garment of the character described having a coat bottom attachable to a jacket in such manner that the garment becomes a coat, whereby the wearer may use the jacket with snow suit pants as when at play, or may use the 15 coat with or without the pants, as when going to school.

Another object of this invention is to provide 20 a sleeved garment having means at the ends of and within the sleeves engaging the wrists of the wearer to prevent cold air from entering 25 the sleeves.

Still another object of this invention is to provide 25 a durable and comfortable garment of the character described which shall be relatively inexpensive to manufacture, attractive in appearance and yet practical and efficient to a high degree in use.

Other objects of this invention will in part 30 be obvious and in part hereinafter pointed out.

35 The invention accordingly consists in the features of construction, combinations of elements, and arrangement of parts which will be exemplified in the construction hereinafter described, and of which the scope of application will be indicated in the following claims.

Fig. 1 is a front perspective view of a garment embodying the invention with parts broken away;

Fig. 2 is a cross-sectional view taken on line 2-2 of Fig. 1;

40 Fig. 3 is a front perspective view of a jacket forming part of the garment embodying the invention and shown without the belt;

Fig. 4 is a front perspective view of a coat bottom for transforming the jacket into a coat;

45 Fig. 5 is a front perspective view of a snow suit embodying the invention and illustrating a modified construction;

Fig. 6 is a view similar to Fig. 3, but showing the jacket with the belt;

50 Fig. 7 is a perspective view of the belt attachable to the jacket when the coat bottom is removed;

Fig. 8 is a perspective view of the bottom of 55 a garment illustrating another modified form of the invention;

Fig. 9 is a cross-sectional view taken on line 9-9 of Fig. 8; and

Fig. 10 is a cross-sectional view taken on line 10-10 of Fig. 5.

Referring now in detail to the drawings, 10 5 designates a combination snow suit and coat embodying the invention and comprising a coat 11 and snow suit pants 12. The coat 11 comprises a jacket 14 forming part of the snow suit and adapted to be converted into a coat, by the addition thereto, in the manner hereinafter appearing, of a coat bottom 15.

The jacket 14 may be of any suitable design 10 10 and has sleeves 16 and overlapping portions 17 and 18 buttoned at the front as by buttons 19. 15 The jacket extends below the waistline to substantially the hips of the wearer, as is usual with jackets of snow suits. Said jacket 11 is provided all around the waistline thereof with a plurality of spaced snap fastener portions 20. 20 A belt 21 disposed around the waist of the jacket has complementary snap fastener portions 22 cooperating with snap fastener portions 20 to attach the belt to the jacket. The belt end 20a projecting beyond the edge of portion 18a of 25 the jacket has a snap fastener portion 23 engaging snap fastener portion 24 on the other belt end 20b terminating short of said edge for connecting the belt ends. It will be noted that 30 there are snap fastener portions 20 on the portion 17 of the jacket covered by the portion 18 of said jacket, and for the purpose hereinafter appearing.

The coat bottom 15 is the portion of a coat 35 from the waist down and has overlapping portions 17a and 18a at the front. Stitched to the upper edge of said coat bottom is a belt simulating member or strip 26, preferably having an extending end 27. On the inner side of the belt simulating member 26 are a plurality of spaced 40 snap fastener portions 29 complementary to snap fastener portions 20 on the waistline of the jacket and so spaced as to be attachable thereto upon removal of the belt 21 for converting said 45 jacket into a coat. A snap fastener portion 30 on the inside of end 27 of said belt simulating member 26 is adapted to be fastened to a snap fastener portion 30a on the outside of said belt simulating member.

When the coat bottom 15 is attached to the 50 jacket the lower portion of the latter, below the waistline, is covered by the upper portion of the coat bottom, and the portions 17a, 18a of said coat bottom overlie the lower ends of 55

the overlapping portions 17, 18, respectively, of the jacket.

The snow pants are worn in the usual manner. When a child goes to school, the coat bottom 5 can be used to provide a full coat. After school, the coat bottom may be removed and the belt 21 applied, to provide the usual play suit with the short jacket giving the wearer more freedom of movement.

10 In Figs. 8 and 9 there is illustrated a modified form of the invention. The garment 18a of said figures comprises a jacket 40 and coat bottom 41. The jacket 40 is similar to jacket 14 except that there is stitched to the waistline thereof, 15 as on line of stitching 43, just above the snap fastener portions 20, the upper edge of a belt simulating member 44 covering said snap fastener portions. Said belt simulating member 44 has an extending end portion 45 overlapping the 20 opposite end 45a of said member and provided with a snap fastener portion 46 attachable to a complementary snap fastener portion 47 on said opposite end.

The upper edge of the coat bottom 41 has on 25 the inner surface thereof snap fastener portions 49 complementary to the snap fastener portions 20 and attachable thereto for adding the coat bottom to the jacket and transforming the latter into a coat. The upper edge of said coat bottom 30 will thus be received beneath the belt simulating member 44 to enhance the appearance of the garment and giving the appearance of a single complete coat without an attached part. The snap fasteners 20 furthermore may be placed on 35 the inside of the belt simulating member 44, in which event the snap fasteners 49 will be on the outside of the coat bottom 41 for attachment to said fasteners 20.

In the form of the invention illustrated in Figs. 40 5 and 10, the jacket 40a is also provided with a belt simulating member 44a at the waistline. Stitched to the inside of said member, adjacent 45 the upper edge thereof, is a slide fastener portion 50. The upper edge of the coat bottom portion 41a is likewise received beneath the belt simulating member 44a and has a slide fastener portion 51 adapted to be attached to said slide fastener portion 50 by a slider 52 which is detachable from one of said portions when moved to fully detaching position. The belt simulating member 44a 50 has an end portion 53 provided with a snap fastener portion 54 attachable to a complementary snap fastener portion 55 on the other end of the belt simulating member.

55 Referring now to Fig. 1 of the drawings, 60 designates the lining of sleeve 16. Stitched to each sleeve lining along line of stitching 61 several inches above the outer end of the jacket sleeve, and projecting toward the sleeve end is 60 an inner short sleeve portion 62 of inelastic fabric, such as lining material, terminating short of said outer end of said jacket sleeve. Stitched as at 64 to the outer end of the inner sleeve 62, is a sleeve portion 66 of elastic material such as 65 knitted jersey preferably looped as shown in Fig. 1. The elastic jersey sleeve 66 encircles and lightly grips the wrist of the wearer to keep the wearer's arms warm.

It will thus be seen that there is provided a 70 device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings, is to be interpreted as illustrative and not in a limiting sense. 5

Having thus described my invention, I claim as new and desire to secure by Letters Patent:

1. In combination, a snow suit jacket extending 10 to the hips of the wearer open at the front forming front edges, a belt simulating member having the upper edge thereof stitched to the waistline of said jacket, a coat bottom having the upper edge thereof received beneath said belt simulating 15 member and detachably attached to said jacket, one end only of said belt simulating member extending beyond one front edge of said jacket, and means for attaching said end of said belt simulating member to the other end thereof. 20

2. A garment comprising a jacket part and a coat bottom part, said jacket part reaching below the waistline and being buttoned at the front and having one vertical edge portion overlapping the other vertical edge portion, means for detachably attaching the upper edge of said coat bottom part to the waistline of said jacket part, whereby said coat bottom part covers the portion of said jacket part below said waistline, a belt simulating member permanently attached to 30 one of said garment parts and covering said detachable attaching means, said coat bottom part having vertical edges aligned with the vertical edges of said jacket and said belt simulating member having an end portion extending beyond 35 the vertical edge of the overlapping portion of the part to which it is attached, and means for detachably attaching said extending end portion of said belt simulating member to an adjacent portion of said belt simulating member overlapped thereby and disposed inward of the other vertical edge of said part. 40

3. A garment comprising a jacket reaching below the waistline and being buttoned at the front and having one vertical edge portion overlapping 45 the other vertical edge portion, a belt simulating member at the waistline of said jacket and above the lower edge of said jacket and having the upper longitudinal edge thereof attached to said jacket, a coat bottom covering the portion of the jacket below the waistline, the upper edge of said coat bottom being received between said belt simulating member and said jacket, a slider actuated fastener portion on said jacket and beneath 50 said belt simulating member and adapted to be covered thereby, a complementary slider actuated fastener portion at the upper edge of said coat bottom and adapted to be joined with the first slider actuated fastener portion by a slider, said slider being detachable from one of said 55 fastener portions at the end of its fully unfastening movement, to permit separation of said coat bottom from said jacket, said belt simulating member having an end portion extending beyond the vertical overlapping edge of said coat, and means for detachably attaching said extending end portion of said belt simulating member to an adjacent portion of said belt simulating member overlapped thereby and disposed inward of the other vertical edge of said jacket. 60

SAMUEL ROSENBLATT.
